UNITED STATES PATENT OFFICE.

FRANK M. GARLAND, OF NEW HAVEN, CONNECTICUT.

AMMUNITION-CLIP.

SPECIFICATION forming part of Letters Patent No. 663,880, dated December 18, 1900.

Application filed February 20, 1900. Serial No. 5,870. (No model.)

To all whom it may concern:

Be it known that I, FRANK M. GARLAND, a citizen of the United States, residing at New Haven, in the county of New Haven and State of Connecticut, have invented certain new and useful Improvements in Ammunition-Clips, of which the following is a specification, reference being had therein to the accompanying drawings.

My invention relates to improvements in ammunition-clips of that class which are designed to be attached to a belt or other like device for conveying cartridges successively to firing mechanism in a firearm.

It is the object of my invention, among other things, to provide means connected with the clip for holding the cartridge against endwise movement, which means will be of such simple design as to add but little to the cost of manufacture of the clips, while providing a positive means whereby all of the cartridges in the several clips will be in line with the others.

To these ends my invention consists of the ammunition-clip constructed and operating substantially as hereinafter described, and more particularly pointed out in the claims.

Referring to the drawings, Figure 1 is a plan view of an ammunition-belt with my improved clips attached thereto. Fig. 2 is a side view thereof, and Fig. 3 is a form of cartridge which I prefer to use in connection with my improved clip.

In the ammunition-belts heretofore made no means have been provided for preventing the endwise movement of the cartridges within the clips. Hence the cartridges were not in line with each other, which frequently caused jamming of the breech-block parts and often a premature explosion of the cartridge. These defects are overcome in my device, where all of the cartridges are presented successively to the breech-block mechanism in the same line.

The clip herein illustrated is made, preferably, of a single piece, being blanked out of a sheet of metal and then bent into its finished form, which comprises a base portion A, shaped at either end so that it may be en-

gaged by the teeth of feed-wheels, spring-arms B B, projecting upwardly from said base portion, upon either side thereof, and turned outwardly at their free ends, forming a flaring throat or entrance between said arms, and inwardly-projecting detents C C, preferably integral with each of said arms. In the form illustrated the detents are made by upsetting the stock forming the spring-arms, which construction is both economical and simple. I do not limit myself, however, to a detent of this form or construction, as any detent will operate equally as well as the one shown. Any preferred means may be used to attach the clips to the belt, the means illustrated consisting of a plurality of rivets D D, passing through the base portion of the clips.

The shell of the cartridges used with these clips has an annular groove E therein, within which the detents C C enter as the cartridges are placed in the clips between the spring-arms.

As all the detents are in a direct line with each other, so will all of the several cartridges in the belt be in a direct line, as they cannot shift endwise within the clips, owing to the engagement of the detents with the annular groove E.

What I claim, and desire to secure by Letters Patent, is—

1. An ammunition-clip, having spring-arms, 80 which arms are adapted to hold a cartridge; and means connected therewith for preventing the endwise movement of the said cartridge within the said arms, the said means consisting of an inwardly-projecting portion 85 engaging with a recess on the said cartridge, substantially as described.

2. An ammunition-clip having a base portion A; spring-arms B B connected therewith and projecting upward therefrom parallel 90 with each other, and means for preventing the endwise movement of a cartridge within the said clip, the said means consisting of the oppositely-disposed inwardly-projecting detents C C upon the inner faces of the said spring-arms, substantially as described.

3. An ammunition-belt having means for removably securing cartridges thereto, the

said means consisting of a clip having spring-
arms between which the cartridges can be in-
serted and means, as detents, upon said
spring-arms which enter a recess in the said
5 cartridges and hold the same against endwise
movement within the said clip, substantially
as described.

In testimony whereof I affix my signature
in presence of two witnesses.

FRANK M. GARLAND.
